ATTORNEY

UNITED STATES PATENT OFFICE

CHARLES MILLER, OF LONG ISLAND CITY, NEW YORK

SHOE LAST

Application filed March 16, 1928. Serial No. 262,072.

This invention relates to shoe lasts, and deals more specifically with a protective device to minimize breakage and mutilation of the lasts during the processes of shoe manufacture.

It is well known, that due to the hammering and pounding to which the lasts are subjected during the shoe manufacturing process, such lasts are considerably mutilated at the rear portion thereof. Considerable breakage of lasts also results from this treatment.

Heretofore, it has been proposed to provide the last with a protective member of a hard material at the top and rear portions thereof, in order to minimize breakage. For this purpose I have found a fibre board material, which is harder than the wood used in the manufacture of lasts, to be most satisfactory. While this material is hard and tough, yet it is dented, scarred, and somewhat deformed by impact on a hard surface.

Also, in the manufacturing process of shoes it is important to have the distance from the upper portion of the rear edge of the last to the point where the vamp contacts with the instep, accurate to a small fraction of an inch. Slight variations in this distance results in an improper fit of the shoe. If this distance is too small it is likely to cause cutting of the foot at the instep or at the lower rear part of the ankle of the wearer. On the other hand if this distance is too great, the shoe wrinkles and bulges in a manner which makes it very undesirable and unsightly. Constant pounding and hammering of the lasts results in deformation thereof particularly at the rear portion, resulting in variations of the aforesaid distance.

It is therefore an object of my invention to provide a last with a protective portion which minimizes breakage and mutilation of the last.

And it is a further object of my invention to provide a last which enables more exact and proper fit of the shoe during the manufacturing processes.

These and other objects of the invention will be readily apparent to those skilled in the art from the following description taken in

connection with the accompanying drawing in which

Fig. 1 is side elevation partly in section of a last embodying my invention.

Figs. 2 and 3 are fragmentary views of the rear portion of lasts showing modifications of my invention.

Referring in detail to Fig. 1 the last 10 is seen to comprise a protective cap or layer 11 provided with a downwardly extending portion 11^a. The cap is formed of a material harder than wood. I have found fibre board most suitable for this purpose but any other suitable material may be used without departing from the spirit of this invention. An insert 12 of wood may be provided to receive the tacks in the lasting operation. Between the cap and the wood of the last proper I place layers 13, 14 and 15 of leather or other resilient material, the layer being held in place in any suitable manner. The layers 13 and 15 serve to absorb strains on the last which are exerted by forces acting in a direction from top to bottom. The layer 14 serves to absorb strains in the last exerted in a direction longitudinally thereof. By virtue of the absorbing layers the protective cap is not deformed by the stresses imposed upon the last during the shoe manufacturing processes. Also, the portion of the last which is cut out to receive the cap is not chipped or broken.

In the modification of Fig. 2 I have shown the cap 11 as being disposed at the rear portion only and not extending forwardly as shown in Fig. 1. Otherwise the structure of Fig. 2 is the same as that of Fig. 1, except for the elimination of the insert 12 which is not an essential element in either case.

In Fig. 3 I have shown another modification of the invention which has the same structure as Fig. 2 except that the layer 15 is omitted.

Having thus described my invention I claim:

1. A wooden last for shoes, a protective cap attached to the top of the heel portion of said last, and a layer of resilient material between said cap and said last and disposed in a direc-

tion substantially normal to the longitudinal axis of the last.

2. A wooden last for shoes, a protective cap attached to the top of the heel portion of said last, a layer of resilient material extending longitudinally of the last and disposed between the last and said cap, and a layer of resilient material extending transversely of the last and substantially at right angles to the heel seat thereof between the last and said cap.

CHARLES MILLER.
